UNITED STATES PATENT OFFICE.

GEORGES CHRISTODULE, OF PARIS, FRANCE.

HERNIA-TRUSS.

No. 923,625.

Specification of Letters Patent.

Patented June 1, 1909.

Application filed December 23, 1907. Serial No. 407,706.

To all whom it may concern:

Be it known that I, GEORGES CHRISTODULE, engineer, subject of Greece, residing at 19 Rue Pierre Levée, Paris, in the Republic of France, have invented new and useful Improvements in Hernia-Trusses, of which the following is a specification.

This invention relates to a hernial truss.

In the annexed drawing, Figure 1 is a vertical section of the truss, Fig. 2 is a plan, the belt being removed, and Figs. 3, 4 and 5 show detail views, in plan, of the collar or washer which holds the spring in position.

In the drawing, *a* represents the cushion or compressor pad, *b* the shackle for securing the spring to the cushion, *c*, *c'* the collars insuring rigidity to the spring, *d* the said spring, and *f* the disk securing the belt to the collar *c*. The shackle *b* is fixed to the pad by means of screws *g* and holds the spring by a pivot *h* entering a perforation. A central screw *j* threaded into the collar *c'* holds the spring on the shackles *b* with the aid of a small screw *p*: To allow of assembling the parts and to make the spring fast, the collar *c'* has a groove *m* in which is engaged the end coil of the spring *d* so as to prevent the latter from turning: Next the belt is the collar *c* with a groove or notch similar to that of the collar *c'* for holding the other end coil of the spring. The extremity *i* of the spring is engaged in a disk *f* which is secured on the collar *c* by means of a

small screw *p*, this collar finally securing the belt *e* by means of a fixing screw *n*. The 35 pad and the spring may be covered either with leather or with cloth.

Having now described my invention, what I claim as new and desire to secure by Letters Patent is:

A hernial truss comprising in combination a belt *e*, a cushion or compressor pad *a*, a coil spring *d* the ends of which are bent up so as to form pivots *h i*, a shackle *b* fixed to the pad and provided with a hole in which is to be engaged one of the bent up ends *h* of the coil spring, a disk *f* fixed to the belt *e* and provided with a hole in which is to be engaged the other bent up end *i* of the coil spring; grooved collars *c* *c'* adapted to engage respectively the last coils of the spring *d*, having a peripheric recess to afford passage to the bent up ends of the coil spring, and secured respectively by means of screws *p* *p'* to the disk *f* and the shackle *b*, and 55 screws *n* *j* securing respectively the grooved collars *c* *c'* to the disk *f* and shackle *b*, substantially as described and for the purpose set forth.

In testimony whereof I have signed my 60 name to this specification in the presence of two subscribing witnesses.

GEORGES CHRISTODULE.
